COMBINED CASING AND NAIL FILE

Jacob M. Weiss, New York, N. Y.

Application September 4, 1941, Serial No. 409,507

1 Claim. (Cl. 132—76.2)

This invention relates to a neck tie holder and has for its object the use of a receptacle for a removable article in addition to its use as a tie holder.

Another object of my invention is to provide for a combination nail file and casing which may be attached to a shirt or other wearing apparel in order to hold a neck tie in position.

A further object of my invention is to provide for a nail file that may be inserted within a casing which will be ornamental and decorative in character so that the nail file will be at one's convenience and ready for use at the same time be used as a decorative and ornamental article.

More particularly, it is an object of my invention to provide a nail file as a decorative ornament which may be used by both men and women upon an article of clothing, so that the nail file will be ready for instantaneous use.

Although nail files have been used with a sheath, heretofore, this article has not been made with attaching means. It is often misplaced and is seldom at one's convenience when required.

I have therefore combined a nail file and casing so that the file can be held within the casing and a clip or pin attached to the casing for convenient attaching to a garment so that the file will be readily accessible, whenever required.

It is understood, of course, that instead of a nail file, other insertable articles may be employed, such as a knife blade, thin screw driver, bottle cap remover, pencil, toothpick or similar articles that are not bulky.

For a fuller understanding of the nature and objects of my invention reference is had to the drawing, in which:

Fig. 1 is a front view of my combined nail file and tie clip.

Fig. 2 is a rear view of the combination shown in Fig. 1.

Fig. 3 is a front view of the nail file that fits within the casing shown in Figs. 1 and 2.

Fig. 4 is a side view of an insertable member and the upper portion of a casing showing a spring member for retaining the file within the casing, the lower portions of the insertable member and the casing being partly broken away.

Referring to the drawing, numeral 20 represents a hollow casing to receive nail file 21 which has a handle 22 attached to wide end of the file. The nail file 21 may be made of various shapes

for different types of files, the file markings bearing on either one or both sides of the file 21. Of course, instead of a file member, it is within the scope of my invention to use a knife blade, bottle cap remover, thin screw driver or other thin articles that may be inserted within a casing 20 or casing of other suitable shape to receive an insertable member. The handle 22 may be of any pleasing design to harmonize with the design of the casing.

The outline of casing 20 is made substantially the outline of the shape of the nail file 21. At the back of casing 20 there is attached by any suitable means, a spring clip 23 so that casing 20 and the insertable member within the casing may be attached to an article of clothing. When used as a tie clip the spring member and casing will hold a neck tie in position.

Referring to Fig. 4, numeral 32 represents a casing having at the upper portion a projection 33 formed from the same material as casing 32, projection 33 having a slight hollow 34 to coact with a nub 35 at the back of the insertable member 36 for retaining said member in position within casing 32.

Although my article is primarily designed as a tie holder for men, it may also be used by women for attachment to the portion of an article of clothing, such as a pocket for use as an ornament, as ornamental clips at the neckline or upon the lapel or belt of the garment.

It is obvious that various changes and modifications will be made in the various details of construction without departing from the general spirit of the combination of the nail file and the casing in the form of pin or clip, as set forth in the appended claim.

I claim:

40 In a combined casing and nail file, a tapered hollow member open at the wider end and closed at the opposite end, a tapered nail file member having a handle at its wider end, said nail file member formed to fit within said hollow member with its handle extending beyond the opening of said hollow member, a knob projecting from the back of said handle, a flexible projecting piece extending beyond said hollow member, said projecting piece having a small hollow to receive said projecting knob.

JACOB M. WEISS.
